United States Patent

Des. 238,309
Patented Dec. 30, 1975

238,309

CIRCUMCISION CLAMP

Carl B. Baumgarten, Houston, Tex., assignor to Gomeo
Surgical Manufacturing Corp., Buffalo, N.Y.

Filed Feb. 19, 1974, Ser. No. 443,376

Term of patent 14 years

Int. Cl. D24—03

U.S. Cl. D83—12 R

fig.1

fig.2

fig.3

FIG. 1 is a perspective view of a circumcision clamp showing my new design;

FIG. 2 is a top plan view thereof;

FIG. 3 is a rear plan view thereof.

The undisclosed side is a mirror image of the side illustrated in FIG. 1.

I claim:

The ornamental design for a circumcision clamp, as shown and described.
